United States Patent Office

Des. 181,734
Patented Dec. 17, 1957

181,734

NECKTIE

Samuel Klaus, Brooklyn, N. Y.

Application October 23, 1956, Serial No. 43,491

Term of patent 14 years

(Cl. D3—16)

Fig. 1

Fig. 2

Fig. 1 is a perspective view of a necktie showing my new design.

Fig. 2 is a cross sectional view taken on line 2—2 of Fig. 1.

The undisclosed faces of the necktie shown in Fig. 1 are conventional and unornamented.

I claim:

The ornamental design for a necktie, as shown and described.
